ABSTRACT OF THE DISCLOSURE

The thermal dealkylation of polyalkyl aromatic hydrocarbons (having from 1 to 3 carbon atoms in each alkyl substituent) is increased by the addition of a radical-forming compound chosen from the group consisting of the C₁ to C₃ alkanols. The radical-forming compound may be added to the hydrodealkylation zone in amounts from about 20 to about 1000 mols per million mols of aromatic hydrocarbon introduced into the hydrodealkylation zone. In the hydrodealkylation of dimethyl naphthalene, the addition of 200 p.p.m. of ethanol was found to increase the once-through conversion from 44.3% to 99.5%, with the production of naphthalene increased from 5.5% to 19.1% and the production of monomethyl naphthalene increased from 23.5% to 72.1%, based on feedstock.

Discussion of the invention

The present invention relates to the hydrodealkylation of alkylated aromatic compounds. More particularly, the present invention relates to the use of a radical-forming additive which increases the efficiency of the hydrodealkylation process, particularly in the treatment of di(C₁ to C₃)alkyl aromatic hydrocarbons. In its most specific aspects, the present invention deals with the addition of 20 to 1000 (preferably about 200) mols of a C₁ to C₃ alkanol per million mols of a dimethyl naphthalene.

The thermal hydrodealkylation of aromatic compounds is well known in the art. An exemplary thermal hydrodealkylation process is carried out in the presence of hydrogen at pressures from about 400 p.s.i.a. to about 800 p.s.i.a. and at temperatures from about 1000° F. to about 1600° F. Hydrogen is added to the dealkylation zone at a treat rate from about 7,000 s.c.f./b. of feedstock to about 15,000 s.c.f./b. of feedstock. The contact time during which the feedstock is present in the dealkylation zone may range from 5 to 40 seconds.

The present invention relates to the dealkylation of poly(C₁ to C₃)alkyl aromatic hydrocarbons, such as polymethyl benzenes, methyl-ethyl benzenes, and polymethyl naphthalenes. Exemplary of the polymethyl benzenes are the xylenes, the isomeric trimethyl benzenes, isomeric tetramethyl benzenes, and mellitene. Exemplary of the polymethyl naphthalenes are the isomeric di-, tri- and tetramethyl naphthalenes. The C₁ to C₃ alkyl substituents may also be mixed, such as 1,5-methyl-3-ethylbenzene. The present invention has been demonstrated to be particularly effective in the dealkylation of dimethyl naphthalene such as 1,2-, 1,3- and 1,6-dimethyl naphthalene. The invention may be used in the dealkylation of substantially pure hydrocarbons, or in streams containing mixtures of the poly-alkyl aromatic hydrocarbons.

The radical-forming additive of the present invention is a C₁ to C₃ alkanol, with ethanol being preferred. The additive may be added to the hydrodealkylation zone in amounts ranging from 20 to 1000 mols of additive per million mols of aromatic hydrocarbon being introduced into the hydrodealkylation zone. The upper limit is set by economics; more could be used if desired. Preferably, when ethanol is being used in the dealkylation of dimethyl

2

naphthalenes, about 200 mols of ethanol will be added per million mols of the dimethyl naphthalene.

In order to illustrate the present invention, examples are given hereinbelow which compare the dealkylation reaction when carried out in the absence of radical-forming additives with the performance when ethanol is added and with the addition of a well-known radical-forming additive, t-butyl peroxide. As will be seen, the ethanol additive is considerably more effective than t-butyl peroxide and is extremely effective as compared to the reaction carried out in the absence of additives.

Examples

Examples 1, 2 and 3 were carried out in a laboratory dealkylation reactor constructed as follows. The main components other than the reactor were a liquid feed pump, a hydrogen metering device, product quench and collecting system, and a tail gas metering and sampling system. The reactor was a 1-inch Schedule 80 stainless steel pipe 30 inches long and was heated in a fluidized sand bath. In each one of the runs a technical mixture of dimethyl naphthalenes was introduced into the reaction zone at a temperature of 1200° F., and at a rate giving the contact time which is shown below in the table. The hydrogen treat rate in each case was obtained by adding heated hydrogen into the reaction zone in admixture with the dimethyl naphthalene feedstock. In those cases where the additives were employed, the additives were added to the dimethyl naphthalene feedstocks before introduction to the reaction zone.

TABLE

	Example 1	Example 2	Example 3
Feedstock		Dimethyl naphthalenes	
Additive	None	(¹)	(²)
Temperature, ° F.	1,200	1,200	1,200
H ₂ treat rate, s.c.f./b.	12,600	11,540	15,000
Contact time, seconds	11.4	10.4	13.8
Once-through yields, wt. percent on F.F.:			
Naphthalene	5.5	8.1	19.1
Monomethyl naphthalene	23.5	24.8	72.1
Conversion, disappearance of dimethyl naphthalenes	44.3	49.6	99.5

¹ t-Butyl peroxide.

² Ethyl alcohol.

By reference to the preceding table, it is seen that the hydrodealkylation reaction carried out in the absence of promoters provided a conversion of 44.3 mol percent. The use of t-butyl peroxide increased the conversion only to 49.6 mol percent. However, ethanol provided a substantially complete reaction, with 99.5% of the dimethyl naphthalenes in the feedstock having disappeared in a once-through process. Note also that the ethanol additive provided a high selectivity to monomethyl naphthalene. In those cases where monomethyl naphthalene is desired as a product, the once-through reaction can be carried out and a preponderantly monomethyl naphthalene product can be recovered by distillation. If, however, naphthalene is the desired product, the hydrodealkylation reaction can be carried out by recycling the monomethyl naphthalene into the hydrodealkylation zone until it has been converted to naphthalene. Note that 19.1 weight percent naphthalene was produced on a once-through basis with the use of ethyl alcohol as compared to 5.5 weight percent when no additive was employed and only 8.1% when t-butyl peroxide was employed.

Thus, it is shown that the ethanol additive of the present invention substantially increases the conversion and selectivity of the hydrodealkylation reaction.

Having disclosed my invention and a preferred mode of carrying it out (in Example 3), what is to be covered by Letters Patent should be governed not by the specific examples herein given, but rather only by the appended claims.

I claim:

1. In the thermal hydrodealkylation of poly(C₁ to C₃)alkyl aromatic hydrocarbons, the improvement of adding to the hydrodealkylation zone from 20 to 1000 mols of a C₁ to C₃ alkanol per million mols of aromatic hydrocarbon.
2. A process in accordance with claim 1 wherein the aromatic hydrocarbon is a polymethyl naphthalene.
3. A process in accordance with claim 1 wherein the alkanol is ethanol.
4. A process in accordance with claim 2 wherein the alkanol is ethanol.
5. A process in accordance with claim 1 wherein the aromatic hydrocarbon is dimethyl naphthalene and the alkanol is ethanol.
6. A process in accordance with claim 5 wherein the ethanol is added at the rate of about 200 mols per million mols of dimethyl naphthalene.
7. A method for thermally hydrodealkylating a C₁₂ to C₁₃ polymethyl naphthalene which comprises
in a hydrodealkylation zone contacting said polymethyl naphthalene in the vapor phase at a temperature from 1100 to 1300° F.,
a pressure from 500 to 700 p.s.i.g., and
a residence time from 5 to 40 seconds
with molecular hydrogen at a rate of 7,000 to 15,000 s.c.f. of hydrogen per barrel of polymethyl naphthalene

while adding to said hydrodealkylation zone from about 20 to about 1000 mols of a C₁ to C₃ alkanol per million mols of polymethyl naphthalene.

5 8. A method in accordance with claim 7 wherein the alkanol is ethanol.

9. A method in accordance with claim 8 wherein the polymethyl naphthalene is dimethyl naphthalene.

10 10. A method in accordance with claim 9 wherein the ethanol addition rate is about 200 mols per million mols of dimethyl naphthalene.

11. A method in accordance with claim 10 wherein the hydrodealkylation conditions are:

a temperature of about 1200° F.,

a pressure of about 600 p.s.i.g.,

a H₂ treat of about 15,000 s.c.f. of hydrogen per barrel of dimethyl naphthalene, and

a residence time of about 13.8 seconds.
